UNITED STATES PATENT OFFICE.

ARTHUR T. KUEHNER, OF ELKRIDGE, MARYLAND.

LOCOMOTIVE JOURNAL-BOX.

1,288,041.

Specification of Letters Patent. Patented Dec. 17, 1918.

Original application filed June 20, 1917, Serial No. 175,905. Divided and this application filed December 31, 1917. Serial No. 209,678.

To all whom it may concern:

Be it known that I, ARTHUR T. KUEHNER, a citizen of the United States, residing at Elkridge, in the county of Howard and State of Maryland, have invented certain new and useful Improvements in Locomotive Journal-Boxes, of which the following is a specification.

This invention relates to a locomotive journal box, being a division of my pending application filed June 20, 1917, serial number 175,905.

The invention has as its primary object to provide a construction wherein the side brasses employed will be mounted to float upon the body of the box so that as the crown brass of the box wears away, the said side brasses will be permitted automatic adjustment to ride vertically within the box and consequently at all times properly fit against the sides of the journal.

The invention has as a still further object to so mount the side brasses, that liners may be readily employed for taking up wear in the said brasses.

A further object of the invention is to provide a construction wherein the brasses will be held in position at one end of the box by a removable face plate employed and will be held in position at the opposite end of the box by a cap plate detachably secured to the box.

And the invention has as a still further object to provide a construction wherein the side and crown brasses may all be removed at either end of the box.

Other and incidental objects will appear as the description proceeds. In the drawings wherein I have illustrated the preferred embodiment of the invention, and wherein similar reference characters designate corresponding parts throughout the several views.

Figure 1 is a horizontal sectional view showing my improved journal box in connection with a pedestal, drive axle and wheel of a locomotive.

Fig. 2 is a sectional view taken on the line 2-2 of Fig. 1 and looking in the direction of the arrows, this view particularly showing the normal disposition of the side brasses of the box.

Fig. 3 is a vertical sectional view on the line 3-3 of Fig. 2 and looking in the direction of the arrows, this view particularly showing the mounting of the springs em-

ployed for holding the side brasses against chattering.

Fig. 4 is a rear elevation showing the mounting of the cap plate employed for holding the side and crown brasses against inward displacement,

Fig. 5 is a sectional view taken on the line 5-5 of Fig. 4 and looking in the direction of the arrows, this view showing the manner in which the face plate of the box is detachably connected thereto, and

Fig. 6 is a perspective view showing the body of the box in detail.

In carrying out the invention my improved journal box is formed with a body 10 recessed medially for receiving the journal 11 of a drive axle 12 through the lower side thereof. This drive axle has been conventionally shown for convenience and at its adjacent end carries one of the drive wheels 13. At its inner end the body of the box is formed with lateral flanges 14 to coöperate with a wedge 15 and shoe 16. The wedge and shoe have also been conventionally shown and are channel shaped in cross section to fit the sides 17 of a pedestal in the usual manner. The sides of the pedestal have also been conventionally shown. Mounted in any approved manner in the lower portion of the journal receiving recess of the box is a cellar 18 which may be of any suitable type.

Overlying the outer end face of the box is a face plate 19. This face plate is, as particularly shown in Fig. 2, cut away to fit around the journal 11, and upon its inner side is, as shown in detail in Fig. 3, formed with a relatively narrow arcuate shoulder 20 to engage within the adjacent end of the crown brass seat 21 at the upper end of the box. Formed through the face plate 19 are a plurality of keyhole slots 22 and engaging through these slots are headed bolts 23 fitted through the body of the box adjacent the corners thereof. As shown in Figs. 2 and 5 of the drawings, the bolts 23 are formed with flat sides for holding the said bolts against rotation. At the outer ends of the bolt receiving openings through the box body, the outer face of the said body is formed with recesses 24 adapted to receive the heads of the said bolts. Normally, the heads of these bolts engage within the reduced portion of the slots 22, as shown in Fig. 2 of the drawings, for rigidly connecting the face plate with the body of the box.

However, as will now be seen in view of the preceding description, the nuts of the bolts 23 may be released when the face plate may be shifted vertically upon the box to dispose 5 the heads of the bolts opposite the enlarged portions of the said slots. The bolts may then be retracted to dispose the heads thereof within the recesses 24 when the face plate may be entirely removed. As will be apparent, 10 this provides a very simple arrangement whereby the face plate may be displaced without the necessity for dismounting the journal box or removing the journal of the axle. In this connection it will be noted that the shoulder 20 will engage within the crown brass seat 21 to coöperate with the bolts 23 for rigidly supporting the face plate in normal position and since the space 15 between the outer face of the box and the wear face of the wheel is restricted, the shoulder is made relatively narrow so that the upper extremity of the plate may be readily swung outwardly to disengage the said shoulder from within the said seat. Furthermore, 20 particular attention is directed to the fact that the plate 19 is formed to overhang the sides of the body 10 of the box at its outer end to provide flanges coöperating with the flanges 14 of the box body, as particularly 25 shown in Fig. 1, for receiving the wedge and shoe.

As particularly shown in Fig. 3 of the drawings, the body 10 of the box is cut away from its inner side face to its outer side face 30 to form the crown brass seat 21 and below this seat, the inner sides of the box body are further cut away to provide oppositely disposed horizontal channels separated from the crown brass seat by horizontal ribs 26. The upper sides of these ribs are formed 35 with beveled faces or shoulders 27 while the lower sides of the said ribs are formed with flat shoulders 28. As in the instance of the crown brass seat, the channels 25 also open 40 through the inner and outer side faces of the box. Removably fitted within the crown brass seat to snugly engage therein is a crown brass 29 which, as shown in Fig. 3 of the drawings, abuts at its outer end with 45 the face plate 19. This crown brass is formed with beveled end edges to seat flat against the shoulders 27 of the ribs 26 so that the said ribs thus support the said brass to overlie the journal 11. The brass is, of course, formed with a curved inner face for receiving the said journal. Removably fitted 50 within the channels 25 are side brasses 30 provided with curved inner faces to fit around the sides of the journal and normally engaging snugly between the journal and the bottom walls of the said channels. These side brasses also abut at their outer ends with the face plate 19 and are mounted 55 to slide vertically within said channels. Interposed between the upper edges of the said

brasses and the shoulders 28 of the ribs 26 are bowed springs 31. The ends of these springs engage the brasses adjacent the extremities thereof while the bowed intermediate portions of the said springs are, as particularly 60 shown in Fig. 3, received within suitable arcuate recesses in the said ribs for holding the springs against accidental displacement.

As will now be clear, the crown brass will 75 rigidly support the journal 11 under the weight of the load while the side brasses present a relatively large bearing area to the journal for taking care of the horizontal forces exerted against these latter brasses. 80 As the crown brass wears away the side brasses will float upwardly within the channels 25 against the tension of the springs 31. An automatic adjustment of the said side brasses is thus permitted so that these brasses 85 will always properly bear against the sides of the journal. Furthermore, since the springs 31 will be normally flexed by the presence of the side brasses within the channel 25, these springs will prevent any chattering or rattling of the said side brasses. When the side brasses become worn, liners 90 may be interposed in the channels beneath the said brasses for taking up such wear and in Figs. 1 and 2 I have shown the use of one 95 of such liners at 32.

Detachably connected to the inner side face of the body 10 of the box is a cap plate 33 for holding the side and crown brasses against inward displacement. This cap 100 plate is formed to fit around the upper extremity of the journal receiving recess in the body of the box and is held by a plurality of bolts 34 embedded in the inner side of the box body, the said bolts extending 105 loosely through the plate and receiving nuts 35 clamping the plate in position. Projecting inwardly from the upper portion of the plate is an arcuate lateral flange 36 fitting within the crown brass seat 21 to engage the 110 curved wall thereof and bearing against the adjacent end of the crown brass 29 for holding said brass in position. The side portions of the plate 33 are formed with inwardly directed flanges 37 fitting within the channels 115 25 against the bottom walls thereof to engage the side brasses 30 for holding these brasses in position. The flanges 36 and 37 of the cap plate will thus rigidly hold the side and crown brasses against inward displacement 120 while the face plate 19 will rigidly hold the said brasses against outward displacement. At the same time the said flanges will act to reinforce the cap plate and will coöperate with the bolts 34 for rigidly supporting the 125 cap plate in position. Should it be desired to remove the side and crown brasses at the inner end of the box, this result may be readily accomplished by simply removing the cap plate. Thus the several brasses of 130

the box may be readily renewed without the necessity for displacing the box. However, should it be desired, for any reason, to remove the brasses at the outer end of the box this result may be readily accomplished by simply displacing the face plate 19. When the cap plate is removed, one or more of the liners similar to that shown at 32, may be readily fitted in position beneath the side brasses and I consequently further provide a very simple arrangement whereby said liners may be placed in position. At the same time, the said liners will be effectually held against displacement between the cap plate and the face plate of the box. These plates, furthermore, will, as particularly shown in Figs. 2 and 4 of the drawings, act to hold the springs 31 against displacement, so that these springs can not become accidentally lost.

Having thus described the invention, what is claimed as new is:

1. A journal box of the character described including a body, a brass removably fitted therein, and means connected to the inner side of the body for holding the brass against inward displacement.

2. A journal box of the character described including a body, a brass removably fitted therein, and a cap plate connected to the inner side of the body for holding the brass against inward displacement.

3. A journal box of the character described including a body, side brasses removably fitted therein, the box being formed to receive liners beneath the said brasses for spacing the brasses laterally, and means connected to the inner side of the box for holding said brasses against inward displacement.

4. A journal box of the character described including a body, a crown brass fitted therein, and side brasses slidably mounted within the body for receiving a journal resting against the crown brass and movable upwardly with the journal as the crown brass wears away.

5. A journal box of the character described including a body, a crown brass fitted therein, side brasses mounted within the body for receiving a journal resting against the crown brass and movable upwardly with the journal as the crown brass wears away, and yieldable means tending to hold the side brasses against upward movement.

6. A journal box of the character described including a body, a crown brass mounted therein, and floating side brasses carried by the body for receiving a journal bearing against the crown brass. 60

7. A journal box of the character described including a body formed with horizontal channels, a crown brass mounted within the body, side brasses slidably vertically within said channels and adapted to fit 65 around a journal resting against the crown brass, and yieldable means arranged within said channels and bearing against the upper edges of the side brasses for resiliently holding the said side brasses against upward 70 movement.

8. A journal box of the character described including a body formed with a crown brass seat and provided with horizontal channels, a crown brass removably 75 fitted in said seat, side brasses removably fitted in said channels, and a cap plate connected to the inner side of the body and provided with flanges extending within said seat and into said channels to engage the 80 crown and side brasses for holding the said brasses against inward displacement.

9. A journal box of the character described including a body provided with a crown brass seat and formed with horizontal 85 channels, ribs separating the seat from the said channels, a crown brass mounted within said seat and supported by said ribs, side brasses slidably vertically within said channels and formed to receive a journal resting 90 against the crown brass, and yieldable means bearing between the said ribs and the side brasses and resiliently holding the said side brasses against upward movement.

10. A journal box of the character described including a body formed with a brass seat, a brass removably fitted in said seat, and means connected to the outer side 95 of the body and engaging in said seat for holding the brass against outward displacement.

11. A journal box of the character described including a body formed with a brass seat, a brass removably fitted in said seat, and a face plate connected to the outer side 105 of the body and engaging in said seat for holding the brass against outward displacement.

In testimony whereof I affix my signature.
ARTHUR T. KUEHNER. [I. S.] 110
